UNITED STATES PATENT OFFICE.

LEROY V. HIATT, OF DOUGLAS, ARIZONA.

DISPLAY RACK.

Application filed June 13, 1922. Serial No. 567,992.

To all whom it may concern:

Be it known that I, LEROY V. HIATT, a citizen of the United States, residing at Douglas, in the county of Cochise and State 5 of Arizona, have invented certain new and useful Improvements in Display Racks, of which the following is a specification.

This invention relates to racks for storing and displaying various commodities and has 10 as its general object to provide an improved rack especially adapted for the storage and display of household articles, such as brooms, mops, brushes, and the containers for various preparations, such as floor oils, 15 and the like.

Another object of the invention is to so construct the rack that within a minimum space it will be adapted to support a maximum number of articles which while compactly associated, may be readily removed 20 from the rack when occasion requires.

Another object of the invention is to provide a rack for the purpose stated which will be inexpensive to manufacture, of a substantial 25 construction, and capable of being shipped in knocked down form and set up by the purchaser without the exercise of any particular skill.

In the accompanying drawings:

Figure 1 is a front elevation of the rack embodying the invention;

Fig. 2 is an end elevation of the rack;

Fig. 3 is a fragmentary perspective view of one lower corner of the rack;

Fig. 4 is a plan view of one upper corner of the rack;

Fig. 5 is a similar view of the other upper corner of the rack;

Fig. 6 is a transverse sectional view substantially on the line 6—6 of Fig. 1 looking in the direction indicated by the arrows.

Generally speaking the rack embodying the invention comprises an upright frame provided with means for supporting thereon various kinds of commodities and this frame is supported in such upright position upon base members which are indicated in general by the numeral 1 and each of which is preferably formed from a single length of 45 bar metal and comprises an intermediate portion 2 and downwardly diverging legs 3 provided at their lower or outer ends with supporting rollers 4 preferably arranged for swiveling movement so that the rack may

be moved about over the floor surface in any 55 desired direction. The base members 1 are connected by spaced parallel longitudinally extending bars 5 bolted to the connecting portions 2 of the two base members and located near the ends of said portions or, 60 in other words, near the points where the legs 3 join the connecting portions.

The frame of the rack is indicated in general by the numeral 6 and is of general rectangular form and comprises vertical 65 side members 7 preferably of bar metal having their lower ends turned at right angles to provide attaching portions 8 which are bolted, as at 9, to the connecting portions 2 of the respective base members 1 substantially at points midway between the ends of said portions. The side members 7 preferably upstand in parallel relation to each other and are connected at their upper ends by an article supporting cross bar indicated 70 by the numeral 10. This bar is preferably of bar metal and has its end portions twisted, as at 11, and right angularly formed as at 12, to provide attaching portions 80 which are bolted as at 13 preferably to the inner sides of the upper ends of the side members 7. By twisting the ends of the cross bar 10, the bar for the greater portion of its length is disposed in upright position in a vertical plane as shown clearly in Fig. 85 1, and is adapted for the support of certain devices which will presently be referred to.

The cross bar 10 relatively braces the upper ends of the side members 7 of the rack frame and preferably these members are 90 further braced by brace rods 14 disposed in crossed relation and bolted at their ends, as at 15, to the inner sides of the said side members 7 and at their point of intersection relatively connected by a bolt 16.

In order to brace the upright side members 7 against displacement in a forward or rearward direction, inverted V-shaped brace members 17 are preferably provided at each end of the frame and have the lower 100 ends of their diverging legs bolted or otherwise secured as at 18 to the ends of the connecting portion 2 of the respective base members 1, the legs of the members 17 at their juncture being bolted as at 19 to the 105 respective side members 7.

As previously stated the cross bar 10 is adapted for the support of suspension de-

5 vices and these devices are in turn adapted to support commodities such as brooms and brushes. Preferably the broom supporting devices are in the nature of arms which are 10 arranged in pairs at opposite sides of the cross bar and are indicated by the numeral 20. These arms are provided at their inner ends with attaching ears 21, and as the corresponding arms of the pairs at opposite 15 sides of the cross bar are correspondingly located, bolts 22 may be passed through said cross bar and each of them through two of the attaching ears 21, each bolt therefore constituting a means for securing to the 20 cross bar 10 two of the said arms and in such manner that the arms will extend in opposite directions from the plane of the cross bar. The arms 20 are preferably inclined slightly in an upward direction 25 toward their outer ends and their outer end portions are preferably turned upwardly at a more acute angle as indicated by the numeral 23. Each pair of arms 20 constitutes a means for supporting a number of brooms, 30 the sticks of which are disposed in depending position between the arms with the shoulders of the broom heads resting upon the upper sides of the arms. Of course, any desired number of pairs of the arms may be provided upon the cross bar and the arms may be of greater or less length so as to support a greater or less number of brooms.

In order that brushes or other small articles may be suspended from the cross bar 10, suspension devices such as shown in Fig. 6 are provided and these devices are indicated by the numeral 24 and each is preferably formed from a length of rod material bent upon itself intermediate of its ends to 40 provide an inverted substantially U-shaped bail portion 25 adapted to be fitted frictionally over the upper edge of the cross bar 10 and thus held firmly in position. Arms 26 extend preferably in a slightly upwardly 45 inclined direction from the lower ends of the bail 25 and outwardly in opposite directions from the plane of the bar 10, and like the arms 20 preferably have their outer end portions turned upwardly at a more acute 50 angle, as at 27, so as to insure against accidental disengagement of the supported articles from said arm. It will be evident by reference to Fig. 1 that brushes or small hand brooms may be suspended from the 55 arms 26, and preferably the devices 24 are arranged between adjacent pairs of the broom supporting arms 20 so that the space between the handles of brooms supported by said arms 20 may be utilized to accommodate the articles suspended from the arms 26, although the said arms 20 may be positioned so close in their paired relation that the heads of the brooms supported thereby 60 will be substantially in contact. In this 65 manner provision is made for the support

of relatively large or bulky articles and smaller articles in the most compact association and yet without interfering in any way with the selective removal of any article from the supporting devices.

In order that a number of mops may be supported by the rack, an open frame 28 is bolted or otherwise secured as at 29' to the outer side of one of the side members 7 near the upper end thereof, and the form of 75 this frame is shown clearly in Fig. 5 of the drawings. The frame is adapted to have the handles of the mops to be supported thereby inserted downwardly through it so that the heads or clamps of the mops will 80 rest upon the upper sides of the side or longitudinal members of the frame. Similarly means is provided at the opposite side of the rack for supporting a number of mop sticks and for this purpose preferably circular rings 29 are secured to the outer side 85 of the respective side member 7 as, for example, by the same bolts 15 which secure the ends of the brace members 14. The mop sticks may be inserted through these 90 rings and they may be supported to rest at their lower ends upon a supporting rest plate 30 disposed at one side upon the upper side of the connecting portion 2 of the respective base member 1, the plate projecting laterally beyond the said base member and beneath the lower ring 29.

The rack is preferably provided with a shelf indicated by the numeral 31 and upon which may be supported various articles, such for example as cans or similar containers for floor polishes, oils and the like. This shelf comprises a preferably metal plate 32 disposed to rest upon the upper sides of the bars 5 and having its corners 105 cut away as at 33 to accommodate the attached lower ends of the legs of the braces 17, the end edges of the plate being cut away at intermediate points as at 34 to fit the lower ends of the respective uprights 7. The end edge portions of the plate are thus disposed to extend above the connecting portions 2 of the respective base members 1, and the same bolts which secure the ends of the bar 5 may serve also to secure the said ends of the plate 32. Likewise bolts 35 may be secured through the said end portions of the plate 32 and also through the portion of the plate 30 which is disposed upon the intermediate portion of the respective base member 1.

In order to prevent the brooms supported by the members 20 swinging back and forth when the rack is moved about from place to place, a cross bar 36 is mounted to extend transversely between the lower portions of the uprights 7 and supports pairs of guard members 37 which correspond in form to the members 20 previously described, the ends 120 of the broom handles being disposed be- 130

tween the members 37 of the respective pairs when the brooms are disposed upon the members 20, for the purpose stated.

Having thus described the invention, 5 what is claimed as new is:

1. In a structure of the class described, a supporting frame structure including a cross bar vertically disposed, and an article supporting member comprising an intermediate 10 bail portion frictionally fitted over the said cross bar and having supporting arms extending laterally and upwardly in opposite directions therefrom.
2. A display rack comprising a base, uprights secured rigidly to and rising from the ends of the base, braces secured rigidly to and extending between the uprights, cross bars secured at their ends to the uprights, one of said bars being located at the upper 15 ends of the uprights and another of said
- bars being located near the lower ends of the uprights and secured thereto by the same elements which secure the braces thereto, and laterally projecting arms secured rigidly on said cross bars, said arms being arranged in pairs and vertically alined whereby to hold suspended articles against swinging.
3. A display rack comprising a base, uprights at the ends of the base, a cross bar 30 connecting the upper ends of the uprights and disposed on edge between the uprights, and article-supporting arms having central bail portions to engage frictionally over the cross bar, the arms extending laterally from the sides of the bail portions and having their end portions inclined upwardly.

In testimony whereof I affix my signature.

LEROY V. HIATT. [L. S.]
